(57) **CLAIM**

The ornamental design for a vision assessment chart, as shown and described.

DESCRIPTION

FIG. 1 is a front elevational view of a vision assessment chart according to an embodiment;

FIG. 2 is a top side elevational view of the vision assessment chart of FIG. 1, with the left, right and bottom sides being identical thereto;

FIG. 3 is a front elevational view of a vision assessment chart according to another embodiment; and,

FIG. 4 is a top side elevational view of the vision assessment chart of FIG. 3, with the left, right and bottom sides being identical thereto.

In the drawings, the broken lines depict environmental subject matter only and form no part of the claimed design.
